UNITED STATES PATENT OFFICE.

WILHELM RIEHM, OF AUGSBURG, GERMANY, ASSIGNOR TO THE FIRM: MASCHINEN-FABRIK AUGSBURG-NUERNBERG, AKTIENGESELLSCHAFT, OF AUGSBURG, GERMANY, A CORPORATION OF GERMANY.

COMBUSTION ENGINE.

Application filed April 11, 1925, Serial No. 22,329, and in Germany August 20, 1924.

This invention relates to combustion engines and more particularly to a device for the solid injection of the fuel (without air) for crude oil motors. In the ordinary devices of this kind, when using gas-oils, and to an especially large extent when using heavy oils, there are formed deposits of carbonized oil, oil coke and the like, which assume the form of tubes depositing in front 10 of the openings of the fuel nozzle. These deposits impair the action of the fuel nozzle to a very large extent because they will prevent a proper distribution of the fuel in the combustion space, by deflecting the jet 15 of fuel in its direction and by finally causing a clogging up of the nozzle.

This invention is based upon the observation that a deposit of carbonized oil does not take place, if the nozzle outlets are exposed to the action of an air or gas-stream. According to this invention the nozzle for the fuel is arranged in such a manner, that it will be systematically exposed to a stream of air or gas. Experiments have proven 25 that in such case the nozzles will remain in perfectly clean condition, so that no troubles will arise and a proper operation of the engine will be possible even when heavy oils are employed. Preferably for this purpose the nozzle for the fuel is so arranged 30 that it will somewhat project out of the interior limiting surface of the cylinder cover, on which it is fastened, so that it will reach into the interior of the cylinder. The nozzle 35 is either so arranged that it will be exposed to a flow of air which is present within the cylinder, for instance in such a way that it will be exposed to the scavenging or charging stream or to the motion of the air, which 40 is generated for the purpose of intimately mixing the fuel with the combustion air. Or a stream of air, for instance the stream of the sucked-in air, is so conducted that it will 45 scavenge the nozzle outlets or orifices of the channels serving for the injection of the fuel.

An especially advantageous effect is obtained, if the air or gas stream is conducted into a chamber surrounding the nozzle, said 50 chamber forming together with the nozzle in the plane of the nozzle outlets or immediately above the same a narrow ring-shaped gap, through which the air or gas stream will enter the cylinder. This stream is

thereby carried under high pressure and with 55 a proper velocity past the nozzle outlets and will thus take away all deposits forming at the nozzle, so that the nozzle will remain always clean on its outside.

The stream of air or gas may be either 60 periodically introduced, that is to say in case of four-stroke engines at every suction stroke by sucking in fresh air, or in case of two-stroke engines during the scavenging period by introducing scavenging air or in- 65 intermittently introduced by injecting from time to time highly compressed air (starting air) during the suction stroke or during the scavenging period. Also in the former case special pressure air may be used for this 70 purpose.

The invention is particularly illustrated in the accompanying drawing in which:—

Fig. 1 is a vertical sectional view through a portion of a cylinder illustrating one form 75 of the invention;

Fig. 2 is a horizontal sectional view through a cylinder illustrating a modification;

Fig. 3 is a fragmentary sectional view 80 through a fuel nozzle, inlet valve, and related parts illustrating another modification;

Fig. 4 is a fragmentary sectional view il- 85 lustrating still another form of the invention.

In the arrangement according to Fig. 1 the nozzle for the fuel projects out of the interior surface *b* of the cylinder cover *c*. The nozzle is so arranged that it will be immediately exposed to the scavenging or the 90 charging stream. In the arrangement shown in Fig. 2 a circular motion of the combustion air is brought about by a deflector fitted to the valve disc which deflects the air in the direction of the arrows *e* as shown. The 95 nozzle *a'* for the fuel, which in this case also projects into the interior limiting surface *f* of the cylinder or the cylinder cover is so arranged that it will be exposed to the motion of the air produced for the purpose of 100 mixing the combustion air with the fuel, as indicated by the arrows *e*.

Fig. 3 shows an arrangement, whereby a screen or deflector *h* is provided in front of the suction valve *g*, said screen serving to 105 deflect the path of the sucked in air and forcing the same to take its way over the nozzle *a'* for the fuel.

According to Fig. 4 the nozzle α^3 is surrounded by a chamber i , which is formed by a properly bent metal sheet j fastened at the cover c^3 of the cylinder. This sheet j is provided at its center with a passage for the nozzle, said passage having such a width, that it will form about in the plane of the orifices of the injection channels or immediately above the same together with the nozzle a narrow ring-shaped channel k . The chamber i is connected through a bore l and the conduit m either with the outer air in the case of four-stroke engines or in the case of two-stroke engines with the container for the scavenging air o or with another container for the pressure air or the gas. In the supply conduit there is inserted a valve, which is so controlled, that it will cause air to pass either periodically into the chamber i , such as in case of four-stroke engines at every suction stroke or in case of two-stroke engines during the scavenging period, or from time to time. In the latter case, in order to obtain a sufficient effect, highly compressed air, for instance starting air must be used. The air discharges through the narrow ring-shaped space k into the cylinder, thereby flowing past the outer side of the nozzle, thus carrying away all deposits forming at the nozzle outlet and permanently keeping all these channels in open condition.

I claim:

1. In an internal combustion engine of the character described, the combination of a cylinder, a fuel-injection nozzle for said cylinder, and means for directing a concentrated fluid stream over the outlet of said nozzle at times intermediate the periods of fuel injection from said nozzle, said means comprising an enclosing member defining a chamber surrounding the outlet end of the nozzle, said enclosing member having an

opening through which said nozzle projects and providing with said nozzle a ring-shaped gap adjacent the nozzle outlet, and means for passing the fluid stream through said chamber and gap past the nozzle into the cylinder of the engine to prevent the building up of carbon deposits thereon. 45 50

2. An internal combustion engine according to claim 1, in which the fluid stream passage is provided with a valve and controlling means for said valve, whereby said valve is adapted to periodically supply fluid to the chamber surrounding the nozzle. 55

3. An internal combustion engine according to claim 1, in which the fluid stream passage is provided with a valve and controlling means for said valve, whereby said valve is adapted to periodically supply fluid to the chamber surrounding the nozzle, and means to connect the fluid passage to a source of air supply to furnish combustion air to said chamber and cylinder. 60 65

4. In a four-cycle internal combustion engine of the character described, the combination of a cylinder having a cylinder head and providing a combustion space, a fuel injection nozzle protruding into said combustion space and having a fuel port adapted to inject fuel therein substantially at the beginning of the combustion stroke, an enclosing member defining a chamber surrounding the protruding end of said nozzle, said enclosing member having an opening adjacent the fuel port of the nozzle, and means connecting said chamber with the atmosphere whereby a concentrated stream of cooling suction air is directed at high velocity over the protruding end of the nozzle on the suction stroke in order to scavenge said nozzle. 70 75 80

In testimony whereof I have affixed my signature.

DR. WILHELM RIEHM.
